UNITED STATES PATENT OFFICE.

LINCOLN PYSHER, OF GRAND JUNCTION, COLORADO.

VEGETABLE SLICER AND SHREDDER.

Application filed May 26, 1925. Serial No. 32,999.

This invention relates to devices for slicing vegetables, and particularly to certain improvements upon the construction illustrated in my Patent #1,039,800 granted to me on October 1, 1912.

In this patent I illustrate a vegetable slicer which comprises a hopper and beneath the hopper a rotatable cylindrical cutter or slicer having a knife disposed in the side wall of the cylindrical cutter, one end of the knife chamber being open and the cylindrical cutter being formed with a conical hub on the inside of the cylindrical cutter acting to push the slices cut by the cutter out of the cutter chamber.

The object of the present invention is to improve upon the construction illustrated in my patent by enlarging the hopper, by doing away with certain details of construction which are expensive and which interfere with the full and best operation of the machine, and to provide a better mounting for the rotatable cylindrical cutter.

A further object is to provide a cutter having not only a slicing knife but a series of knives projecting outwardly from the cylindrical cutter and acting to cut the potatoes into strips to thereby provide for making what are known as shoestring potatoes, these knives being so arranged that no matter how the potato may shift within the hopper the potatoes will be properly cut into strips while being sliced.

A still further object is to provide improved means whereby the cutter cylinder may be moved from its housing and the knives sharpened, repaired or replaced and the device thoroughly cleaned.

Other objects will appear in the course of the following description.

My invention is illustrated in the accompanying drawing, wherein:

Figure 1 is a vertical sectional view of a vegetable slicer and cutter constructed in accordance with my invention;

Figure 2 is a section on the line 2—2 of Figure 1;

Figure 3 is an elevation of the cutting cylinder showing the slicing knives;

Figure 4 is an elevation of the cutting cylinder showing the knife 27.

Referring to this drawing, 10 designates a body which is preferably, though not necessarily, cylindrical in form, this body at its upper end being formed to provide a hopper 11 which has a cross sectional area

the same as the cross sectional area of the body 10. The intermediate portion of the body 10 has its opposite walls cut away, as at 12 and 13, and disposed within this portion of the body 10 is a cylindrical knife carrier or cutter 14. This has preferably the form shown in Figure 3, that is, it is cast from one piece of material and formed on its ends with the flanges 15. The cylindrical cutter is open at one end, as at 16. Its opposite end, however, is closed by an integrally cast web 17. This web extends inward from the adjacent flange 15 and then extends axially in the form of a cone, as at 18, this cone having a length approximately two-thirds the length of the cylindrical cutter. The cone is capped, as at 19, and engaging with these screw-threads is a spindle 20 carrying a crank handle 21 at its outer end.

For the purpose of mounting this spindle on the body 10, I provide a plate 22 which is engaged with the side wall of the body 10 in any suitable manner, as by screws or the like, this plate having a conical bearing 23 which fits the recess 24 forming the inner face of the conical portion 18, and through this conical portion 24 of the plate the spindle 20 passes. This conical portion, therefore, forms a bearing for the spindle 20. The cylindrical cutter 16 is so cast as to form a longitudinally extending slot 25, one or more of which is formed with a seat 26 for a knife 27, the knife being held to the seat by means of screws or like devices. This knife 27 overhangs the opposite wall of the slot 25 and is spaced therefrom.

Diametrically opposite the slot 25 the cylinder is reduced in thickness to form a seat 28, and disposed on this seat 28 is the plate 29 attached thereto by screws or like devices, this plate carrying a series of outwardly projecting knife blades 30. These are preferably struck up from the plate 29, though not necessarily so, and preferably have a depth of about a quarter of an inch more or less. These knives are very thin and are arranged in pairs, as illustrated, the first pair being relatively close together or having a distance equal to the thickness of a potato shoestring, the next pair being further spaced apart a distance approximately equal to two potato shoestrings, the next pair being still further spaced apart, and so on, but each knife being spaced from an adjacent knife a distance equal to the thick-

ness of a potato shoestring. Below the cutting cylinder the lower portion of the body 10 is formed to provide opposed clamping jaws 31 and 32, the jaw 32 being provided 5 with a screw 33 whereby the device may be clamped upon a table.

It is to be noted that the plate 22 inasmuch as it rests against the outer face of the body 10 constitutes the rear wall of 10 a recess within which the rear end of the cutting cylinder is disposed and that the flanges 15 fill said recess thus formed, thus preventing any vegetable matter from working down between the rear end of the cutting cylinder and the plate 22. It will further be seen that the depth of the front flanges 15 and rear flanges 15 is equal to the depth of the knives 30 so that by removing the set screw that holds the handle 20 21 in place the cutting cylinders 15 may be withdrawn through the front opening.

While, of course, it is possible to release the screws holding the plate 22 to the rear of the body and thus remove the cutting cylinder through the rear opening of the body, ordinarily the cutting cylinder will be removed through the front opening and the plate 22 be left in place. I have found, however, that by forming this plate 22 as 30 a separate piece from the body that the machine may be more readily and thoroughly cleaned whenever necessary than if the plate 22 is formed as part of or integral with the body. It will be seen that with 35 this construction the cylinder is not screwed in place upon the end of the spindle 20 and therefore cannot be jammed but when it is desired to remove the cylinder 16 for cleaning or for the substitution of one cylinder for another it is only necessary to remove the set screw which holds the handle 21 in place and then the cylinder may be readily withdrawn. If the spindle 20 was 40 permanently mounted within the bearing 23, then it would be necessary to unscrew the cylinder 16 when it was desired to remove it and because of the very small hand hold, and because of the tendency to jam upon the screw threads, the spindle would in 45 many cases not be easy to remove.

In the use of this device, the knives 30, as the cylinder is rotated, pass through the potato or other vegetable their full depth but do not cut anything off, merely forming 55 parallel kerfs in the vegetable. The slicing knife 27 then operates and cuts off what would be a relatively thick slice and delivers it through the slot beneath its edge from the side of the cylinder and out into 60 the receptacle, and by reason of the fact that the upright knives have gone through the vegetable the vegetable falls apart in long strips the full length of the vegetable, thus forming the "shoestrings" for which 65 the machine is particularly adapted.

While I have illustrated this device as being of a size particularly adapted for cutting shoestring potatoes, I do not wish to be limited to this as the device may be made in any size so that the machine may 70 be used by dairymen to cut their root crop and vegetables for their cattle and may be used for slicing and dicing vegetables for soup, cutting kraut or even by sugar beet factories. The device will, of course, slice 75 fruit as well as vegetables, may be used for shredding cabbage, lettuce, celery, etc., and inasmuch as the vegetables are cut into uniform sizes and slices it is obvious that the vegetables when cooked will be uniformly cooked throughout, that is, each piece will be as properly cooked as any other piece.

This device, while particularly designed for making shoestring potatoes, may also be used for dicing potatoes and other vegetables, particularly onions. An onion is formed of separate, more or less concentric layers of rings and, therefore, the splitting knives will cut these layers into squares 80 and these squares are delivered out through the chamber 16 into a receptacle. The same is true of cabbage which thus may be diced or shredded. In order to dice potatoes, however, they are first formed into shoestrings 85 in the manner described and then carried through the machine a second time, which 90 will obtain the desired result.

I do not wish to be limited to the exact construction illustrated, as this might be varied in many ways without departing 95 from the spirit of the invention.

I claim:

1. In a vegetable cutter, a body having a hopper at its upper end and below the hopper being formed with a circular opening in its front wall and the rear wall having a circular recess, a cutting cylinder having its opposite ends flanged, said flanges fitting the front opening and the recess respectively, and a spindle extending through the rear wall of the body concentric to the recess therein and having a handle operatively engaged with said cylinder.

2. In a vegetable cutter, a body having a hopper at its upper end and below the hopper being formed with a circular opening in its front wall and the rear wall having a circular recess, a cutting cylinder having outwardly projecting knives and having its opposite ends flanged, said flanges having a depth equal to the depth of the knives and fitting the front opening and the recess respectively, a spindle engaged with said cylinder and extending through the rear wall of the body and slidably mounted therein, and a handle detachably engaged with the rear end of the spindle and when in place holding the cylinder in place within said body.

3. In a vegetable cutter, a body having

a hopper at its upper end and below the hopper being formed with a circular opening in its front wall and in its rear wall, a plate attached to the outer face of the body and extending over the rear circular opening, said plate having a central bearing, a cutting cylinder having its opposite ends flanged, said flanges fitting the front opening and the rear opening respectively whereby the cylinder is supported at its opposite ends, said cylinder having a wall at

one end formed with a concentric, hollow projecting portion, a spindle engaged with this portion and extending rearward through said bearing, and a handle detachably engaged with the rear end of the spindle and when in place holding the cylinder in position within the body. 15

In testimony whereof I hereunto affix my signature.

LINCOLN PYSHER.
